UNITED STATES PATENT OFFICE

165,383

CHILD'S WALKER-STROLLER

Moises B. Lorenzana, Chicago, Ill., assignor to Storkline Furniture Corporation, Chicago, Ill.,
 a corporation of Illinois

Application September 15, 1951, Serial No. 16,654

Term of patent 7 years

(Cl. D14—14)

To all whom it may concern:

Be it known that I, Moises B. Lorenzana, a person of Philippine origin, and at present an applicant for citizenship of the United States, and a resident of the city of Chicago, county of Cook, State of Illinois, have invented a new, original, and ornamental Design for a Child's Walker-Stroller, of which the following is a specification, reference being had to the accompanying drawing, forming a part thereof, in which:

Figure 1 is an isometric view of a child's walker-stroller showing my new design and showing the device, with the pushing handle unfolded to an operative position for use as a stroller;

the device, with the pushing handle folded to an inoperative position for use as a walker; and

I claim:

The ornamental design for a child's walker-stroller, substantially as shown.

MOISES B. LORENZANA.
